UNITED STATES PATENT OFFICE.

SAMUEL BLACKMAN, OF PHILADELPHIA, PENNSYLVANIA.

DESIGN FOR A BOTTLE.

Application filed August 7, 1922. Serial No. 3,307. Term of patent 3½ years.

To all whom it may concern:

Be it known that I, SAMUEL BLACKMAN, a citizen of the United States, residing at Philadelphia, in the county of Philadelphia and State of Pennsylvania, have invented a new, original, and ornamental Bottle, of which the following is a specification, reference being had to the accompanying drawing, forming a part thereof.

I claim:

The ornamental design for a bottle.

SAMUEL BLACKMAN.
